UNITED STATES PATENT OFFICE

ALFRED KINZBACH, OF SOUR LAKE, TEXAS

VALVE MECHANISM

Application filed May 8, 1928. Serial No. 276,000.

With the above and other objects in view this invention relates to certain novel features of construction, operation and arrangement of parts an example of which is given in this 5 specification and illustrated in the accompanying drawings, wherein:—

Figure 1 shows a horizontal sectional view of two of the tanks of a tank farm, showing the branch pipes, of the outlet line, connected 10 into said tanks and equipped with the improved type of valve mechanism.

Figure 2 shows a fragmentary vertical sectional view of a tank showing the valve mechanism therein shown in section, and

15 Figure 3 shows an end view of the valve mechanism partly in section.

Referring now more particularly to the drawings, wherein like numerals of reference designate similar parts in each of the 20 figures the numerals 1 and 2 designate two of the tanks of a tank farm into which are connected the branches 3 and 4 of the main outlet line 5. Outside of the tanks these branch lines are equipped with the respective 25 shut off valves 6 and 7.

Within each tank there is a valve casing, as 8, substantially, tubular in form. This casing is secured, at its outer end, to the tank wall in alignment and communication with 30 the corresponding branch line and the inner end of the casing has an inlet opening 9. The casing 8 has a horizontally disposed lengthwise partition 10 and above it the transverse partition 11, thus separating the casing into 35 a flow chamber 12, an inlet chamber 13 and an outlet chamber 14. The arrangement of these partitions may, of course, be changed to provide the chambers referred to, the specific arrangement shown not being essential. 40 The chamber 13 communicates with the interior of the tank, through the opening 9 and the chamber 14 communicates with the corresponding branch line.

The partition 10 has an opening through 45 which the chamber 13 may communicate with the chamber 12, and this opening is surrounded by the valve seat 15. Upstanding from the casing 8 and aligned above the seat 15 there is a tubular valve guide 16 having opposing, 50 aligned vertical bearings 17. Vertically mov-

able in said guide is a sleeve valve 18, whose lower end is closed and tapered to conform to, and close, the seat 11. The valve 18 has laterally extending rods 19, 19, fixed thereto and working through the respective bearings 55 17 and attached to the outer ends of the rods 19 are the relatively large cylindrical floats 20, 20, preferably formed of sheet metal.

Leading from the flow chamber 12 into the outlet chamber 14 there is an opening having a surrounding seat 21 and an upwardly opening back pressure valve 22 controls said opening. This valve has an upstanding stem 23 which works in a guide 24 attached to the upper side of the casing 8.

At the present time when the contents of an oil tank is delivered into the line the corresponding, gate valve, as 6 or 7 is opened and the oil is thus permitted to drain out, but while being drained the presence of an attendant is necessary to close said opened gate valve before the inner end of the branch line connected into said tank is uncovered and air entrapped in said line. With the type of valve herein described the presence of an attendant is not necessary as the valve 18 will automatically close before the inlet 9 is uncovered and exposed to the air. Furthermore both of the tanks 1 and 2 and the other tanks of the farm, connected into the line 5, may be 70 drained at the same time and the back pressure valves 22 will prevent the back flow of fluid from one tank into another.

While I have shown what I now consider the preferred form of the invention it is obvious that mechanical changes may be made therein and equivalents substituted for the parts shown and I reserve the right to make such changes and substitutions as may be found desirable and such as may be comprehended within the scope of the appended claims.

What I claim is:—

1. A valve mechanism for controlling the flow of fluid from a tank and including a casing anchored to the tank and having an inlet in the tank and an outlet, partitions fixed in said casing separating the same into an inlet chamber into which said inlet leads, an outlet chamber from which said outlet leads

and a flow chamber, openings connecting the flow-chamber with the inlet and outlet chambers, and surrounded by valve seats, and valves controlling said seats, and a float connected to one of said valves, a valve guide attached to said casing in which one of said valves works, a float outside of the guide connected to said last named valve, and means limiting the range of movement of said valve.

2. A valve mechanism including a casing having an inlet and outlet, partitions in said casing separating the same into an inlet chamber into which said inlet leads, an outlet chamber from which said outlet leads, and a flow chamber, openings connecting the flow chamber with the inlet and outlet chambers, and surrounded by valve seats, valves controlling said seats, a float connected to one of said valves, a tubular valve guide attached to and upstanding from said casing, having a vertical bearing and in which one of said valves works, a float outside of the guide, and means working laterally through said bearing, and fastened to said float and to the valve in said guide.

3. A valve mechanism for controlling the outflow of fluids from a tank and comprising a casing within and anchored to the tank and having an inlet within the tank and an outlet from the tank, partitions fixed in said casing separating the same into an inlet chamber into which the inlet leads, an outlet chamber from which said outlet leads and a flow chamber, there being openings surrounded by valve seats and connecting the flow chamber with the inlet and outlet chambers, valves controlling said openings and arranged to be closed by gravity, a tubular valve guide standing up from the inlet chamber in which the valve controlling the corresponding seat is fitted, said guide having a vertical slot, a rod attached to the said valve and extending out through said slot and a float fixed to the outer end of said rod.

45. In testimony whereof I have signed my name to this specification.

ALFRED KINZBACH.
